BINARY COUNTING SYSTEM

Alan S. Fitzgerald, Mill Valley, Calif.

Application June 15, 1956, Serial No. 591,631

19 Claims. (Cl. 307—88)

This invention relates to electrical counting circuits, and more particularly to binary counting systems, such as those which form the basis of digital computing apparatus.

Binary counting systems of the above mentioned character include, as the principal functional element, bi-stable electrical systems of the type commonly referred to in the art, as "flip-flops." In general a flip-flop may be considered to be any electrical or other system which possesses the property of having two or more stable states of operation, which it is capable of assuming the maintaining under the same conditions of energization and without change in the circuit elements or connections.

Devices having this characteristic are familiar in the art of mechanical engineering and are referred to as "toggle systems." Examples of analogous electrical systems are the well known Eccles-Jordan electronic flip-flop and the magnetic amplifier type of flip-flop disclosed by the present inventor in U. S. Patent No. 2,027,312.

All of the systems above adumbrated possess the additional characteristic that they are capable of transfer from one of the said conditions of stability, to the other, in response to a control impulse or signal of the appropriate nature.

The present invention is directed to the character of the said impulse or signal, and to the manner of response of the flip-flop thereto. One of the most familiar examples of the "toggle" type of response is that which is manifested by the type of electrical switch so nomenclated. In the simplest form of toggle switch, "on" or "off" action, as desired, is obtained by actuating the switch in one or other of two different directions or senses.

Another type of manually operated toggle switch, involving structure additional to that included in the simple type above cited, is identified by the description "canopy" or "chain-pull" type.

When a switch of this latter type is actuated successively, in a single sense only, it gives, alternately "on" and "off" action. Types of relays which respond in this manner are well known and are sometimes called "impulse" relays. When relays of this type are repeatedly energized they will alternately open and close the contacts. It is well known that devices capable of this kind of response form the basis of the binary systems which are the foundation of the digital computer art.

It is, accordingly, an object of my invention to provide a method and means whereby the basic type of electrical flip-flop, which acts in the manner of a simple toggle switch, may be given the more complex characteristics of the "chain-pull" type of toggle action. That is to say, my invention is a solution of the problem of deriving, from a system which, basically, gives bi-lateral action in response to control impulses of bi-lateral sense, a system in which each successive impulse, in a series thereof of unilateral sense, produces a response opposite in sense to that which occurred as a result of the preceding signal impulse.

It is another object of my invention to provide a system

2

of the above-described character, capable of emitting, upon response to a succession of incoming signal impulses, a series of output pulses of like character such that a plurality of such systems may be cascaded indefinitely in accordance with the digital computer art.

It is yet another object of my invention to provide a type of electrical counting stage which is distinguished from the prior art in that no symmetrical relation is necessary between the pair of flip-flops in each stage, whereby careful matching of tubes, resistors, transistors, or magnetic core devices is unnecessary.

It is a further object of my invention to provide a binary element which, while it is applicable generally, is particularly adapted to the use of magnetic amplifier structure and thus especially suitable for use in applications in which magnetic amplifiers are for other reasons essential elements; as for example, in converting from an analogue computer of magnetic amplifier type to a digital scaler.

Another object of my invention is to provide a type of electrical counting stage which is extremely positive in its action with regard to reversal of state.

These and other novel features which I believe to be characteristic of my invention will be set forth with particularity in the appended claims. My invention itself, however, both as to its organization and method of operation, together with further objects and advantages thereof, may best be understood with reference to the following description taken in connection with the accompanying drawings, in which:

Fig. 1 is a schematic diagram illustrating the basic principle of my invention;

Fig. 2 is an electrical circuit diagram illustrating an embodiment of my invention utilizing flip-flops of magnetic amplifier type; and

Fig. 3 is a block diagram of a binary counting or scaling circuit employing a plurality of stages in cascade.

Referring to the drawings I show in Fig. 1 an electrical system for responding in alternate sense to a succession of impulses of like sense, and including a first bi-stable element indicated in the diagram as flip-flop A and a second bi-stable element flip-flop B.

The flip-flops A and B may be of different kinds or of similar type or character but are not necessarily of the same magnitude as to their quantitative electrical outputs, since there is no symmetrical relation therebetween. In order to disclose and to describe the operation of my invention in the most direct and simple manner I have omitted, in Fig. 1, conventional details of the structure pertaining to the flip-flops A and B since the precise nature of these elements is not a primary feature of my invention.

My invention may be practised effectively with any type of bi-stable element capable of remaining in one or other of two states of stability, one of these furnishing a substantially greater output than the other; and which can be caused to transfer from either of these two stable states to the other by momentary application of signal impulses of appropriate and differing sense.

For example the flip-flops A and B may comprise snap-action relays, electron discharge devices, semi-conductor contact devices such as transistors, magnetic amplifiers, or any other electroresponsive devices capable of delivering output in both alternating and unilateral form, and controllable by signals of different sense.

For the purpose of illustration and explanation of the basic features of my invention, the two flip-flops A and B are depicted in Fig. 1, according to the conventional block diagram method, in the form of rectangles each provided with terminals for power supply, for input and output, and windings or other receiving circuit elements to which, in the particular type of flip-flop em-

ployed, it is customary to apply the controlling signal impulses.

In the interest of brevity of text the condition of stability giving the lower value of output will hereinafter be referred to as the "flop" state, and that giving the higher output, the "flip" condition. In like manner the action of transfer from the lower output condition to the high output state will be referred to as "flip" and the opposite action "flop".

Let it be supposed, by way of example, in Fig. 1, 10 that the flip-flops A and B are of a type which may be caused to flip and flop by the momentary application of a D.-C. signal of reversible polarity, as, for instance, would be the case if the flip-flops A and B were snap-action polarized relays or magnetic amplifier elements such as those disclosed in the above cited U. S. patent. For convenience in explanation we will refer to the polarity of signal which gives rise to the flip action as positive and that which causes the flop state as negative.

Referring again to Fig. 1, I show the flip-flops A and B energized with A.-C. of a suitable frequency from the source 1 through binding posts 2, 3 and 12, 13. I show also output binding posts 4, 5 at which the output of A may be utilized. A.-C. operated flip-flops in general include rectifying elements. This is the case for example in Patent 2,027,312. Accordingly, output from such devices is obtainable either before or after rectification in the form of A.-C. or D.-C. current as desired. In Fig. 1, flip-flop A delivers its output at binding posts 4, 5 in the form of D.-C.

I show also pertaining to flip-flop A three additional binding posts 6, 7, 8 and control elements 10 and 11. Control element 10 is connected to binding post 6 and control element 11 to post 7. Binding post 8 provides a common return for both 10 and 11.

The control element 10 or 11 is to be understood to be the flip-flop element which receives the controlling impulse or signal energy applied for the purpose of causing the bi-stable system to transfer from one condition of stability to the other. For example, electronic devices are customarily controlled by some form of voltage-drop producing device such as a resistor traversed by a current of variable magnitude; other flip-flop devices such as relays or magnetic amplifiers may be controlled by ampere-turn producing means such as a flow of current in a suitable magnetizing winding.

Thus in Fig. 1 the circuit elements shown at 10 and 11 are to be understood to be controlling means, appropriate to the type of flip-flop used at A and B. It is further to be understood that when either of the elements 10 or 11 is energized in the sense indicated in Fig. 1 by an upward directed arrow, the control effect is exerted in a direction such as to tend to cause the flip-flop A to be flipped; that is to say, to be transferred from the low current state to the condition of stability which gives the higher current output. The opposite effect is denoted by an arrow pointing downwards.

Thus, as indicated by the direction of the arrows in Fig. 1, the effects of 10 and 11, respectively, are in opposing senses. Thus if the effects of these two control elements are substantially of equal magnitude no controlling influence will be exerted upon the flip-flop A. But if the effect of 10 exceeds that of 11 there will be a consequent tendency to cause A to be flipped. On the other hand, if 11 exerts a greater effect than 10, the sense of the resultant effect will be in the flop direction. In other words, if 10 preponderates over 11, the flip-flop A will assume a state such that a current of substantial magnitude may be furnished at binding posts 4, 5. Conversely, if 11 preponderates over 10 the flip-flop A will assume the other condition of stability in which the current furnished will be of a relatively lower magnitude.

Referring now to the flip-flop B, I show two binding posts 14, 15, corresponding, in flip-flop B, with 4 and

5 in flip-flop A, from which rectified output from B may be obtained. I show also a second pair of binding posts 24 and 25 included in flip-flop B, from which energy may be withdrawn, in alternating form, previous to the rectification procedure for energizing binding posts 14, 15.

Whereas, in the case of flip-flop A it is only necessary that the flop current be substantially lower than the flip current, a slightly different characteristic is necessary in respect to flip-flop B; in this case it is desired that the output current, both D.-C. at binding posts 14, 15, and A.-C. at binding posts 24, 25, in the flop condition, be reduced to approximately zero.

I show also, included in the flip-flop B, a pair of controlling means 20 and 21, corresponding to the similar elements 10 and 11 of flip-flop A and likewise exerting effects in opposing sense as indicated by arrows in the same manner as those pertaining to 10 and 11. I show binding posts at 17, 18, for providing connection to the control means 21.

In the case of the control circuit 20, in flip-flop B, according to the operation of my invention, it is not necessary that the effect exerted by 20 be variable. Accordingly, in order to make the diagram as simple as possible I have omitted connections necessary for supplying 20 with a current or voltage of fixed magnitude and have, instead, indicated by + and - insignia that this circuit element is to be so energized.

In the operation of my invention the function of the flip-flop B is a simple one. It is required only that it respond positively and in inverse sense to the action of A; that it shall instantly flip when A flops, and flop when A flips.

The flip-flop A is controlled directly by the incoming signals, which are assumed to be unidirectional impulses of unchanging polarity, delivered at binding posts 22, 23.

By hypothesis both of the flip-flops A and B are assumed to be responsive to control impulses of alternately reversing sense or polarity. Accordingly, an instrumentality is required which will convert the said uniform pulse signals into effects applied to flip-flop A, of alternately reversing sense or polarity.

This result is obtained by an arrangement whereby both of the control elements 10 and 11 of the flip-flop A are simultaneously energized by the incoming pulse signal. This is accomplished by providing a divided signal input circuit so that two parallel paths exist between binding posts 22 and 23. One of these includes the control circuit 11 and a resistor of fixed value 27. The other path energizes the second control circuit 10 through a resistance network 30 which is not of fixed value.

The turns of 10 and 11 are so proportioned that if the value of fixed resistor 27 is greater than that of the variable resistance 30, the signal pulse, dividing and passing through both the control circuit 10 and control circuit 11, which it will be recalled are connected in opposition, causes A to flip. Conversely, if the value of 30 exceeds that of 27 the signal impulse causes A to assume the flop condition. If the value of the variable resistor could be caused to increase and to decrease alternately with each successive pulse signal, A could be made to flip and flop with alternate incoming signal impulse.

This I accomplish by employing, for the variable resistance 30 a non-linear resistance element. It is well known that many types of boundary layer devices such as are employed in dry type or contact rectifiers exhibit marked non-linear characteristics. I, therefore, show in Fig. 1 the variable resistor 30 as comprising a network consisting of a pair of conventional full-wave or bridge-type rectifier stacks 26, 28. The A.-C. terminals of the rectifiers are connected in parallel. The D.-C. terminals are connected together - to +. With this connection if alternating current is applied to the A.-C. terminals no output will be derivable from the D.-C. terminals. Instead, the two rectifiers 26 and 28 are short-circuited be-

tween themselves and direct current circulates therethrough. As a result, neglecting filterable effects, no voltage, either unidirectional or alternating, will appear at the short-circuited D.-C. terminals, as a result of the A.-C. energization of 30.

Between these terminals there will exist nevertheless a resistance value; and because of the non-linear characteristic of the selenium or other element used, this resistance will be relatively high if there is little or no current flowing, and very considerably lower if the two stacks are energized with alternating current so that a substantial direct current flows through the short-circuit path. The path lying between the two pairs of conjoined D.-C. terminals is considered to constitute the variable resistance.

The value of this variable resistance has to be controlled at will to produce the desired result. This can be readily done by appropriately energizing this non-linear network with alternating current. The basis of the method of connecting the two rectifier stacks is that this arrangement results in decoupling between the A.-C. and the D.-C. circuits, as in a magnetic amplifier. The network 30, of course, is not intended to act as an amplifier and does not do so. But no voltages emanating from the source from which the non-linear network is energized appear in the signal input circuit.

Accordingly, the non-linear network 30 is connected to binding posts 24, 25 so as to be energized by means of the A.-C. output of flip-flop B. Any time that B is in the flip condition a substantial A.-C. current flows through 30 whereby the resistance presented to the component of the signal impulse passing therethrough is lower than that of the fixed resistor 27. However, when B is in the flop state, in accordance with the characteristics hereinbefore designated in reference to the flip-flop B, in which the output thereof is reduced to zero, there will be no energization of the network 30. Thus the resistance presented to the portion of the signal impulse which passes through 10 and 30 will be substantially increased as a result of which the current in 27 will be greater than that in 30, whereat A will be flopped.

Referring now to flip-flop B, as previously indicated, it is desired that B should flip and flop in inverse sense in direct response to the transfer of A from the flip to the flop condition or vice versa. By hypothesis, the flip-flop B, has similar characteristics to those of A; that is to say it is responsive to control impulses of alternately reverse sense. The output of the flip-flop A, it is to be noted, is variable in magnitude but it is not reversible in sense or polarity. Accordingly, I provide the desired controlling effect upon the flip-flop B by connecting the output binding posts 4, 5 of A to the control binding posts 17, 18 of B so that the rectified current from the output of A energizes the control element 21 of B in the sense which tends to cause the latter to assume the flop condition. The energization of 21, accordingly, will have high value when A is flipped and a value when A is flopped which will still be of the same sense, but will be reduced in magnitude. I therefore provide also the bucking or opposing control element 20 which latter I energize, in the sense which tends to cause B to flip, with a predetermined constant magnitude intermediate between the high and low values of the energization of 21. Thus when A is in the flip condition so that 21 receives the high output current, the effect of 21 is greater than that of 20; accordingly the resultant effect of 20 and 21 is in the sense which tends to cause B to assume the flop condition. Again, when A is flopped so that the energization of 21 is reduced, 20 preponderates and the net effect is to cause B to flip.

It will be evident to those skilled in the art that the chain of response action above described will produce the desired result. Let it be assumed for example that the system of Fig. 1 be at rest with A flopped. Under this condition B is flipped and 30 is energized with A.-C. Suppose now a single control or count pulse is delivered at 22,

23; the resistance of 30 being low the effect of 30 exceeds that of 27 and A is flipped; whereat B is instantly flopped, de-energizing 30. It is evident that a second pulse of the same character as the first one will now produce the opposite effect. A third pulse will find the system in the condition postulated at the commencement of the present paragraph and the alternately opposite response will evidently result in respect to all succeeding pulses.

The operation of a single binary element has now been completely described and explained. However, if such a system is to be used for digital counting purposes, the circuit must emit a signal of the same character as that by which it is actuated.

I show in Fig. 1 structure for accomplishing this result. 15 I connect to the binding posts 14 and 15 an output type transformer 16. It will be recalled that rectified output from the flip-flop B is derivable from these binding posts. This D.-C. output current, varying between the flop value and the zero flop value is demodulated and clipped by the 20 transformer 16, a capacitor 31 and a half-wave rectifier 34, according to the manner well understood by those skilled in the art. I show also in Fig. 1 binding posts 32, 33 to which the transformer 16, capacitor 31 and half-wave rectifier 34 are connected, thus furnishing at 32 and 33 25 at one-half the count frequency, unidirectional uniform pulses of the identical character to those supplied at binding posts 22 and 23 by means of which my invention, according to Fig. 1, is actuated.

I show, in more complete detail, in Fig. 2 an embodiment of my invention in which flip-flops A and B comprise bi-stable magnetic amplifier elements. Magnetic amplifier flip-flops are well known to those skilled in the art. For example, a bi-stable magnetic amplifier circuit is disclosed by the present inventor in U. S. Patent 2,027,312. I wish 30 it to be particularly understood that the arrangements disclosed in Fig. 2 are shown by way of example only. Any desired type of magnetic amplifier flip-flop may be employed in practicing my invention. I show in Fig. 2 some of the more simple arrangements in order to facilitate description and explanation of the manner of working of my invention. More complicated types of magnetic amplifier, capable of higher speeds of response, are well known in the art.

In Fig. 2 I show A.-C. source 1, flip-flop A and B, fixed 45 resistor 27 and non-linear network 30 all as shown and described in reference to Fig. 1 and bearing like reference numerals. I show also input binding posts 22 and 23, transformer 16, capacitor 31, half-wave rectifier 34 and output binding posts 32, 33. Referring to flip-flop A I 50 show a pair of magnetic cores 35, 36 carrying windings 37, 38. The magnetic cores 35, 36 preferably of a magnetic material furnishing an approximately square hysteresis curve, may be of any suitable configuration, as for example, of toroidal form. I show on each of the toroids 55 35, 36, four additional pairs of windings 40, 41, 42 and 43.

On referring to Fig. 2 it will be noted that each of these pairs consists of one winding situated on core 35 connected directly to another winding correspondingly positioned on core 36. Due to space exigencies on the diagram and in 60 order to avoid confusion thereon due to multiplicity of reference numerals, these are not repeated for both of the units of each pair of windings. It is to be understood that the winding which is directly connected to a winding to which the numeral is appended, is intended to be likewise referred to thereby. Arrows are appended to each individual winding indicating the sense of the M. M. F. set up by the current flowing therein in accordance with the operation of my invention. It will be noted that the M. M. F.'s are in the same direction for each pair of 65 windings.

Of the four windings shown on the cores 35, 36 the pair 40 corresponds to the control element 10 in Fig. 1 and the pair 41 corresponds in function to the control element 11 in Fig. 1. Pair 42 comprises the feedback winding. The windings 43 comprise the bias, the func-

tion of which is well understood by those skilled in the art, and requires only unidirectional excitation of a substantially constant magnitude.

I show also in Fig. 2 a pair of half-wave rectifiers 44 and 45 to which windings 37 and 38 are connected. It will be apparent to those skilled in the art pertaining to magnetic amplifiers that the windings 37 and 38 are those commonly referred to as the A.-C. windings; and that the method of connection of the A.-C. windings 37 and 38 and the half-wave rectifiers 44 and 45 comprises a self-saturating type of magnetic amplifier requiring an alternating current supply having a mid-point tap. Accordingly, I show in Fig. 2 three binding posts 46, 47 and 48 energized from the mid-point tapped secondary 51, of a transformer 50, the primary winding 52 of which is energized from the A.-C. source 1.

Referring to the diagram, it will be apparent that, in accordance with the proper connections for self-saturation, one extremity of the winding 37 is connected with binding post 46, and the corresponding extremity of winding 38 connects with binding post 48. Thus the output circuit of flip-flop A, including the feedback winding 42 and the control element 21 of B, derives from the junction point of half-wave rectifiers 44, 45 and returns to binding post 47.

Referring to flip-flop B, I show a pair of similar toroids or other cores 55, 56 carrying A.-C. windings 57 and 58. I show also three pairs of D.-C. windings 60, 61, 62. Pair 60 corresponds to winding 20 in Fig. 1 and pair 61 corresponds to winding 21 in Fig. 1. Pair 62 is the feedback winding.

I show also in Fig. 2 a counterpoise impedance 63, the function of which is as follows. As hereinbefore indicated it is desired that the flop value of the output current of B be zero. In a simple type of magnetic amplifier flip-flop such as for example that disclosed in U. S. Patent 2,027,312, the flop value is a current of relatively low magnitude. It is a characteristic of magnetic amplifiers of elemental type that the output current, in the absence of input, is not zero. This current is often referred to in the art as the quiescent current, and there are a number of different methods known to those skilled in the art for compensating for this quiescent current so as to provide that zero output when there is zero input. Reference may be made to the teachings of the present inventor published in A. I. E. E. Transactions, part 1, volume 71, page 7.

These methods are equally applicable to the bi-stable characteristic. That is to say, the flop current may be treated as the quiescent current. Thus I show in Fig. 2 the method of compensation which is disclosed in Fig. 1-B of the above-cited A. I. E. E. reference and which corresponds with Fig. 2 of U. S. Patent 2,027,311. Thus the counterpoise impedance 63 corresponds in function to the similar circuit element 55 shown in the patent.

According to this arrangement, which is not of the self-saturating type, I show in Fig. 2 the two windings 57 and 58 connected in series, in opposite sense, with one extremity of winding 58 connecting with binding post 48. I show an extremity of the counterpoise 63 connecting with binding post 46. Accordingly, the output circuit for flip-flop B derives from the junction point between 57 and 63 and terminates at binding post 47. Thus the output circuit of flip-flop B includes the non-linear network 30 and the rectifier 64, the D.-C. output of which latter is connected to supply the feedback winding 62 and the primary winding of transformer 16. Thus, in accordance with the general arrangements outlined in reference to Fig. 1, flip-flop B delivers A.-C. output to the non-linear network 30 and rectified output to transformer 16.

As has been hereinbefore explained, both the bias winding 43 of flip-flop A and the winding 60 of flip-flop B are required to be supplied with direct current excitation of fixed appropriate magnitude. Accordingly, in Fig. 2, I provide the windings 43 and 60 with numbers of turns commensurate with their relative excitation magnitudes,

and I connect these windings in series, in the proper sense, as indicated by the arrows in Fig. 2. I supply these windings with current from a rectifier 66, energized from binding posts 46 and 48, and I include resistors 67 and 68 in series with the D.-C. and A.-C. connections of 66 for current adjusting purposes.

I show also in Fig. 2 a filter choke 65 connected in series with the rectified output of the flip-flop B to the transformer 16. A filter capacitor 70 is likewise shown connected across the D.-C. terminals of the non-linear network 30. The function of both of these circuit elements is conventional.

I show also in the diagram a series resistor 59 included in the rectified output circuit of flip-flop A, and a shunt resistor 69 connected in parallel with the A.-C. terminals of 30. These latter resistors are not essential functional elements but may be found convenient in some instances for trimming or adjustment purposes in the event of impedance incompatibility between the various circuit components.

The manner of operation of the system shown in Fig. 2 is essentially in accordance with the explanation and description hereinbefore set forth with reference to Fig. 1. Thus, the windings 40, 41, in Fig. 2, are identical in function with 10, 11, in Fig. 1; and the windings 60, 61, correspond exactly with 20, 21. In Fig. 2 the rectified output of flip-flop A is delivered between the junction point of 44, 45, and the binding post 47; this corresponds with 4, 5, in Fig. 1. Similarly, the D.-C. output of flip-flop B is delivered at binding posts 14, 15, in Fig. 1, and, in Fig. 2, at the connections of 62, 65 to the transformer 16. In like manner the A.-C. output of B is, in Fig. 2, delivered between the lower A.-C. connection of the rectifier 64 and the junction point of 57 and 63, which corresponds with the binding posts 24, 25, in Fig. 1.

Other details of the circuit of Fig. 2 pertain to the particular type of flip-flop employed, rather than forming a part of my invention per se, and are included only by way of illustration.

40. I show in Fig. 3 a block diagram depicting how three binary systems, in accordance with the circuit of Fig. 2, would be connected together for application in the field of digital computing and scaling. Such an assembly would give a count of eight. The methods of adapting larger numbers of binaries to count in decades are well understood by those skilled in the art pertaining to digital computers.

Thus in Fig. 3 I show A.-C. supply 1, transformer 50, as in Fig. 2, and at 71, 72, and 73, three complete binary systems comprising substantially all of the structure disclosed and described in reference to Fig. 2.

55. The three binaries 71, 72, and 73 are depicted in block diagram form, and show, pertaining to each of the three rectangles representing a complete binary, binding posts 22 and 23 for receiving the input pulse, binding posts 32 and 33 for delivering the output pulse, and binding posts 46, 47, and 48, energized from the transformer 50.

As shown in Fig. 3, the output binding posts 32 and 33 of the binary 71 are connected to the input binding posts 22 and 23 of 72. Thus, assuming a series of count signals to be delivered to the input of 71, impulses of one-half of that frequency are delivered by 71 to 72.

60. In like manner the output of 72 is connected to the input of 73 and delivers thereto impulses of one-quarter the original count frequency.

The third binary, 73, delivers, to the output binding posts 32, 33, thereof, a series of impulses of one-eighth the frequency of the count signals applied to the input binding posts 22, 23, of 71.

70. Although I have chosen a particular embodiment of my invention for the purpose of explanation, many modifications thereof will be apparent to those skilled in the art to which it pertains. My invention, therefore, is not to be limited except in so far as is necessitated by the prior art and the spirit of the appended claims.

What I claim as new and desire to secure by Letters Patent of the United States is:

1. A binary counter comprising a first and a second bi-stable electroresponsive system, each having two stable operating states, the two states of each giving different characteristic output energy, means for causing said first bi-stable system to control in inverse sense said second bi-stable system, a source of control impulses, means connecting said impulse source to control said first bi-stable system; means connecting said second mentioned bi-stable system with said connecting means, whereby alternate control impulses produce opposite effects upon said first bi-stable system in accordance with the condition of stability of said second bi-stable system.

2. A binary counter comprising a first and a second bi-stable electroresponsive system, each having two stable operating states, the two states of each giving different characteristic output energy, means for causing said first bi-stable system to control in inverse sense said second bi-stable system, a source of control impulses, means connecting said impulse source to control said first bi-stable system, decoupling means connecting said second mentioned bi-stable system with said connecting means, whereby alternate control impulses produce opposite effects upon said first bi-stable system in accordance with the condition of stability of said second bi-stable system.

3. A binary counter comprising a first and a second bi-stable system, each having two stable operating states, the two states of each giving different characteristic output energy, means for causing said first bi-stable system to control in inverse sense said second bi-stable system, means for channelling a series of control impulses to said first bi-stable system, means connecting said second mentioned bi-stable system with said channelling means, whereby said control impulses produce different effects upon said first bi-stable system in accordance with the condition of stability of said second bi-stable system, and means for excluding energy from said second bi-stable system from said first bi-stable system.

4. A binary counter comprising a first and a second magnetic amplifier, each having two stable operating states, the two states of each giving different characteristic output energy, means for causing said first magnetic amplifier to control in inverse sense said second magnetic amplifier, means for supplying a series of control impulses to said first magnetic amplifier, and means connecting said second mentioned magnetic amplifier with said supplying means, whereby said control impulses produce different effects upon said first magnetic amplifier in accordance with the condition of stability of said second magnetic amplifier.

5. A binary counter comprising a first flip-flop and a second flip-flop, means whereby when said first flip-flop is flipped said second flip-flop is caused to flop, and whereby when said first flip-flop is flopped said second flip-flop is flipped, and pair of bridge-type rectifiers having their A.-C. connections paralleled and having their D.-C. outputs connected in series additively to form a closed circuit, means including said rectifiers for supplying a series of count signal impulses to said first flip-flop, means for deriving A.-C. output from said second flip-flop, and means for energizing said rectifiers with said A.-C. output.

6. A binary counter comprising a first bi-stable system and a second bi-stable system, each of said bi-stable systems having two conditions of stability a high output condition and a low output condition, means whereby when said first bi-stable system is in the high output condition said second bi-stable system is caused to assume the low output condition and whereby when first bi-stable system is in the low output condition said second bi-stable system is caused to assume the high output condition, a pair of bridge-type rectifiers having their A.-C. connections paralleled and having their D.-C. outputs connected in series additively to form a closed circuit, means including said rectifiers for supplying a series of

count signal impulses to said first bi-stable system, means for deriving A.-C. output from second bi-stable system, and means for energizing said rectifiers with said A.-C. output.

5 7. A binary counter comprising a first bi-stable system and a second bi-stable system, each of said bi-stable systems having two conditions of stability, a high output condition and a low output condition, means for causing said first bi-stable system to control, in inverse sense, said second bi-stable system, a pair of bridge type rectifiers having their A.-C. connections paralleled and having their D.-C. outputs connected in series additively to form a closed circuit, means including said rectifiers for supplying a series of count signal impulses to said first bi-stable system, means for deriving A.-C. output from said second bi-stable system, and means for energizing said rectifiers with said A.-C. output.

15 8. A binary counter comprising a first and a second electrical amplifier, each having two stable operating states, the two states of each giving different characteristic output energy, means for causing said first electrical amplifier to control in inverse sense said second electrical amplifier, means for supplying a series of control impulses to said first electrical amplifier, and means connecting said second mentioned electrical amplifier with said supplying means, whereby said control impulses produce different effects upon said first electrical amplifier in accordance with the condition of stability of said second electrical amplifier.

20 9. A binary counter comprising a first and a second electrical amplifier, each having two stable operating states, said first amplifier having a high output condition and a low output condition and said second amplifier having a condition furnishing an output and a condition furnishing zero output, means derived from the output of said first electrical amplifier to control in inverse sense said second electrical amplifier, means for supplying a series of control impulses to said first electrical amplifier, and means connecting said second mentioned electrical amplifier with said supplying means, whereby said control impulses produce different effects upon said first electrical amplifier in accordance with the condition of stability of said second electrical amplifier.

25 10. A binary counter comprising a first and a second electrical amplifier, each having two stable operating states, the two states of each giving different characteristic output energy, said first amplifier furnishing unilateral output, said second amplifier furnishing both unilateral and alternating output, means for causing said first electrical amplifier to control in inverse sense said second electrical amplifier, means for supplying a series of control impulses to said first electrical amplifier, variable means included in said supply means, and means for energizing said variable means from the alternating output 30 of said second amplifier, whereby said control impulses produce different effects upon said first electrical amplifier in accordance with the condition of stability of said second electrical amplifier.

35 11. A binary counter comprising a first and a second electrical amplifier, each having two stable operating states, the two states of each giving different characteristic output energy, said first amplifier furnishing unilateral output, said second amplifier furnishing both unilateral and alternating output, means for causing said first electrical amplifier to control in inverse sense said second electrical amplifier, means for supplying a series of control impulses to said first electrical amplifier, variable means included in said supply means, means for energizing said variable means from the alternating output of said second amplifier, whereby said control impulses produce different effects upon said first amplifier in accordance with the condition of stability of said second amplifier, and means for deriving from the unilateral output 40 of said second amplifier a series of control impulses 45 50 55 60 65 70 75

of the same character as said first mentioned series of impulses but having a differing frequency.

12. A binary counter comprising a first bi-stable electrical system and a second bi-stable electrical system each of said systems having two conditions of stability a high output condition and a low output condition, means for causing said first bi-stable system to control in inverse sense said second bi-stable system, means for deriving A.-C. output from said second bi-stable system, means for delivering a series of count signal impulses to said first bi-stable system, and means for energizing said delivering means with said A.-C. output, said delivering means consisting of a network of rectifier elements so connected together as to pass said signal impulses to said first bi-stable system and to exclude therefrom said A.-C. output energy.

13. A binary counter comprising a first bi-stable electrical system and a second bi-stable electrical system each of said systems having two conditions of stability a high output condition and a low output condition, means for causing said first bi-stable system to control in inverse sense said second bi-stable system, means for deriving A.-C. output from said second bi-stable system, means for delivering a series of count signal impulses to said first bi-stable system, and means for energizing said delivering means with said A.-C. output, said delivering means including a network of variably unilaterally conducting elements connected together so as to effect decoupling between said A.-C. output energy and said first bi-stable system.

14. A binary counter comprising a first bi-stable electrical system and a second bi-stable electrical system each of said systems having two conditions of stability a high output condition and a low output condition, means for causing said first bi-stable system to control in inverse sense said second bi-stable system, means for deriving A.-C. output from said second bi-stable system, means for delivering a series of count signal impulses to said first bi-stable system, and means for energizing said delivering means with said A.-C. output, said delivering means including a network of variably conducting elements permitting passage of said signal impulses to said first bi-stable system but excluding said A.-C. energy therefrom.

15. A binary counter comprising a first bi-stable electrical system and a second bi-stable electrical system each of said systems having two conditions of stability a high output condition and a low output condition, means for causing said first bi-stable system to control in inverse sense said second bi-stable system, means for deriving A.-C. output from said second bi-stable system, means for delivering a series of count signal impulses to said first bi-stable system, and means for energizing said delivering means with said A.-C. output, said delivering means including variable impedance means for permitting passage of said signal impulses to said first bi-stable system but excluding said A.-C. energy therefrom.

16. A binary counter comprising a first bi-stable electrical system and a second bi-stable electrical system each of said systems having two conditions of stability a high output condition and a low output condition, means for causing said first bi-stable system to control in inverse sense said second bi-stable system, means for deriving A.-C. output from said second bi-stable system, means for delivering a series of count signal impulses to said first bi-stable system, and means for energizing said delivering means with said A.-C. output, said delivering means including non-linear resistance means effecting decoupling between said A.-C. output energy and said first bi-stable system.

17. A binary counter comprising a first bi-stable electrical system and a second bi-stable electrical system each of said systems having two conditions of stability a high output condition and a low output condition, means for causing said first bi-stable system to control in inverse sense said second bi-stable system, means for deriving A.-C. output from said second bi-stable system, means for delivering a series of count signal impulses to said first bi-stable system, and means for energizing said delivering means with said A.-C. output, said delivering means including non-linear attenuating means effecting decoupling between said A.-C. output energy and said first bi-stable system.

18. A binary counter comprising a first bi-stable electrical system and a second bi-stable electrical system each of said systems having two conditions of stability a high output condition and a low output condition, means for causing said first bi-stable system to control in inverse sense said second bi-stable system, means for deriving A.-C. output from said second bi-stable system, means for delivering a series of count signal impulses to said first bi-stable system, and means for energizing said delivering means with said A.-C. output, said delivering means including semi-conductor means effecting decoupling between said A.-C. output energy and said first bi-stable system.

19. A digital counter comprising a first and a second electroresponsive system each having a plurality of stable operating conditions giving differing output magnitudes, means for causing said first system to control in inverse sense said second system, means for deriving A.-C. output from said second system, means for supplying a series of count signal impulses to said first electroresponsive system, means for energizing said supplying means with said A.-C. output, said supplying means including controllable variably transmitting means permitting delivery of said count signal impulses to said first electroresponsive system but excluding therefrom said A.-C. output energy from said second electroresponsive system.
